United States Patent Office

Des. 233,079
Patented Oct. 1, 1974

233,079

EMBOSSED PLASTIC SHEET MATERIAL OR SIMILAR ARTICLE

Frank C. Burroughs, Reynoldsburg, and Jared R. Kies,
Newark, Ohio, assignors to Owens-Corning Fiberglas
Corporation

Filed Sept. 7, 1972, Ser. No. 287,181

Term of patent 14 years

Int. Cl. D5—06

U.S. Cl. D87—3

Fig. 2

FIG. 1 is a plan view of an embossed plastic sheet material showing our new design, a design unit being shown within the rectangle marked off, the repeat being indicated by the extensions beyond the border of the rectangle; and

FIG. 2 is an enlarged plan view of a portion of the design unit shown in FIG. 1 showing the embossment at substantially actual size.

We claim:

The ornamental design for an embossed plastic sheet material or similar article, substantially as shown and described.
